UNITED STATES PATENT OFFICE

NELS T. NELSON, OF ATTLEBORO, MASSACHUSETTS, ASSIGNOR TO J. F. STURDY'S SON CO., OF ATTLEBORO FALLS, MASSACHUSETTS, A CORPORATION OF MASSACHUSETTS

BUCKLE FOR WRIST WATCH STRAPS

Application filed May 9, 1930. Serial No. 450,967.

This invention relates to a clasp or buckle particularly adapted to be used on a wrist watch strap or bracelet, and has for its object to provide a construction by which one of the parts may be releasably clamped at any desired point along the strap.

A further object of the invention is to provide an adjustable buckle member with a clamp lever which will not interfere with the clasping of the two parts together, and which will provide a ready adjustment along the length of the strap.

A still further object of this invention is to provide means for adjustably securing one part of the buckle along the strap, and locking the securing means of this part in position by the other part of the buckle when held in clasped engagement therewith.

With these and other objects and advantageous features in view, the invention consists of a novel arrangement of parts more fully disclosed in the detailed description following, in conjunction with the accompanying drawings, and more particularly set forth in the appended claim.

In the drawings:

Fig. 1 is a top plan view of the buckle with its two parts in clasped position;

Fig. 2 is a top plan view of the body or adjustable part of the buckle as secured in position on the strap with the plate part shown in Figure 1 removed therefrom;

Fig. 3 is a section on line 3—3 of Figure 1;

Fig. 4 is a perspective view of the body member with its clamp lever removed;

Fig. 5 is a perspective view of the clamp lever;

Fig. 6 is a perspective view of the body member with its clamp mounted therein in working position upon the strap; and

Fig. 7 is a sectional view on line 7—7 of Figure 3.

In the use of wrist straps for securing a wrist watch about the arm of the wearer, it is found desirable to loop a portion of the strap through the bail of the wrist watch or other eye or bail portion by doubling the strap upon itself and securing it in a desired position to cause the strap to snugly

embrace the wrist, but permitting enlargement to remove the same over the hand, and in order to provide a positive and yet easily operable buckle member which may be moved and secured in adjusted positions along the strap, I have provided a body which will receive a strap and have mounted a clamp lever therein to be swung to grip the strap between it and the body to frictionally hold the body member in position, and have also provided on this body means to receive the plate member of the buckle which may be attached to the end of the strap for releasably securing the plate in position; and the following is a detailed description of the present embodiment of this invention illustrating the preferred means by which these advantageous results may be accomplished.

With reference to the drawings, 10 designates the end portion of a strap to which the plate member 11 of the buckle is suitably secured by means of an eye clamp 12 secured thereto and upon the strap part 13 there is mounted the body member 14 of the opposite part of the buckle which consists of a bottom wall 15 with slots 16 and 17 extending transversely with relation to the strap when mounted thereon, and side walls 18 extending from the bottom wall 15 and along the sides of the strap part 13. Pairs of openings 19, 20 are formed in these side walls, and between the side walls there is mounted a clamp lever 21 which is L-shaped and provided with trunnions 22 adjacent the juncture of the arms 23 and 24 of the L lever, which trunnions extend into one pair of openings 19 to pivotally mount the clamp lever in the body member. The openings 19 are in line with the slot 16 so that the arm 23 extends toward the slot 16 in the bottom wall and forces the strap part 13 into this slot to frictionally engage with the edges thereof when in clamped position, as illustrated in Figure 3.

This lever is held in clamped position by detents 25 upon the flange 26 of the arm 24 of the lever which snap into the openings 20 due to the resiliency of the side walls 18 and hold the lever in clamping position. The

flanges 26 also serve to prevent the lever from being swung beyond its maximum clamping position and cause the top of the lever to present an extended surface to form a seat for the plate 11.

Knobs 27 are mounted upon the side walls 18 and the plate member 11 is notched at 28 to receive the knobs 27, which may snap through the notches with a portion of their 10 rounded surfaces extending over the top of the plate member 11 to hold it firmly in contact with the broad surface of the clamp which forms a seat for the same and prevents rocking and liability of detachment 15 of this plate member when in secured position; and at the same time as this plate member is held against the clamp, the same is prevented from swinging on its trunnions as a pivot to release the strap which is secured thereby.

In order that the clamp may be moved to released position upon removal of the plate member, I have provided a finger piece 29 to facilitate engagement and movement of 25 the same, and have notched the clamp as at 30 on either side to prevent the clamp from engagement with the knobs 27.

The body member 14 may be moved along the strap part 13 to any desired position, and 30 the plate member 11 which is secured to the end of the strap may be engaged to draw the strap tightly about the wrist and be snapped into engagement with the body member for holding the parts in desired 35 relation.

While I have described certain construction forms which embody the principles of my invention, it is obvious that other desired changes in arrangement may be made within 40 the spirit and the scope of the invention as defined in the appended claim.

I claim:

A strap buckle comprising a body member having a bottom wall having spaced 45 slots extending transversely with respect to the longitudinal extent of the strap, side walls secured to said bottom wall to extend along the side edges of the strap and having two pairs of oppositely disposed openings 50 in its side walls located in line with said slots, an L-shaped clamp lever provided with trunnions pivotally mounted in one of said pairs of openings and provided with detents adjacent one end of the lever arm to be re- 55 leasably received in the other pair of openings to hold the lever in clamped position, knobs mounted on said side walls, said lever being provided with side notches to prevent its contact with said knobs, and a plate 60 member adapted to be secured to an end of the strap and provided with notches to receive said knobs and hold said plate and body secured together.

In testimony whereof I affix my signature.
NELS T. NELSON.
